DESIGN FOR A TOY TYPEWRITER

Thomas Raymond Arden, Baldwin, N. Y., assignor
to American Flyer Mfg. Co., Chicago, Ill., a corporation of Illinois

Application August 16, 1933, Serial No. 49,037

Term of patent 7 years

To all whom it may concern:

Be it known that I, THOMAS RAYMOND ARDEN,
a citizen of the United States, residing at Baldwin, in the county of Nassau, and State of New York, have invented a new, original and ornamental Design for Toy Typewriters, of which the following is a specification, reference being had to the accompanying drawing, forming part thereof.

The figure is a perspective view of a toy typewriter, showing my new design.

I claim:—

The ornamental design for a toy typewriter,
as shown.

THOMAS RAYMOND ARDEN.
